UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

RIBBON SPOOL FOR TYPEWRITERS.

Application filed April 5, 1920. Serial No. 371,216.

To all whom it may concern:

Be it known that I, OTTO A. HOKANSON, a citizen of the United States, residing at Woodstock, in the county of McHenry and 5 State of Illinois, have invented certain new and useful Improvements in Ribbon Spools for Typewriters, of which the following is a specification.

This invention has for its object the provision of a device of the class named which shall be of improved construction and operation.

The invention is exemplified in the combination and arrangement of parts shown 15 in the accompanying drawing and described in the following specification, and it is more particularly pointed out in the appended claims.

In the drawing—

20 Fig. 1 is an elevation of a ribbon spool embodying one form of the present invention;

Fig. 2 is a top plan view of the spool shown in Fig. 1;

25 Fig. 3 is a vertical section of a ribbon spool showing a slightly modified form of the invention; and

Fig. 4 is a fragmentary top plan view of a portion of the device shown in Fig. 3.

30 In the embodiments of the invention shown in the drawing, the parts are all made of stamped sheet metal and the spool includes a top rim or flange 10 and a lower flange 11. Between the flanges 10 and 11

35 there is interposed the spool core 12 which is a sheet of metal bent in the form of a hollow cylinder. The sheet metal core 12 has its edges spaced apart however to leave an opening between the edges at one side

40 of the spool, as shown at 13. The ends of the core member 12 are provided with tongues 14 which project through slots 15 in the flanges 10 and 11 and are bent over to secure the parts of the spool together. The

45 slots 15 are formed in a rib 16 struck outwardly from the flanges 10 and 11 and curved to conform to the shape of the core member 12. The upper flange 10, as illustrated, is also provided with a strengthen-

50 ing rib 17 near the outer edge of the flange. It may also be cut away, as shown in broken lines at 18 in Fig. 2 of the drawing, and be provided with radial ribs 19 extending along the spokes formed by the cut-away portions

55 18. A circular opening 20 is preferably

formed in the upper flange 10 upon which the finger of the operator may be placed to rotate the spool by hand.

A portion of the lower flange 11 is punched from the flange, as shown at 21, and bent inwardly, leaving an opening in the lower flange adjacent the space 13 between the edges of the core member 12. This opening is for the purpose of admitting a control finger to cooperate with the ribbon for reversing the direction of rotation of the spools in a manner well known in the art. The material punched from the opening 21 is not entirely severed from the flange 11, but remains intact with the remaining portion of the flange along the inner edge 22 of the opening 21. This cut-out portion is bent inwardly to form a tongue 23 shown in broken lines in Fig. 1. It will be noted that the opening in Fig. 2 is provided with lateral projections 24 which result in wings 25 on the inwardly bent tongue 23. These wings 25 are bent into circular formation, as shown in Fig. 2, so that they form a bearing for the ribbon spool shaft and a guide for directing the spool onto the shaft. Where such a bearing is provided the ribbon spool shaft may be shorter than would otherwise be necessary, for the reason that the shaft does not need to extend upwardly through the opening in the upper flange 10 to provide an upper bearing for the spool.

55 In order to attach the end of the ribbon to the core member 12 barbs 26 are punched from the core member and are bent outwardly from the surface of the core member so that they may penetrate the ribbon. Two sets of barbs 26 are provided, as shown in Fig. 2, the barbs of the different sets being pointed in opposite direction. This makes it possible to secure the ribbon to the spool so as to be wound thereon in either direction and permits each spool to be used on either the left or the right-hand side of the typewriter. This arrangement is also useful where both ends of the spool are alike as it will permit the spool to be used with either side up.

60 In the form of the invention shown in Figs. 3 and 4 the punched in tongue 27 is struck from a rectangular opening 28 and the projecting wings shown at 25 in Figs. 1 and 2 are omitted. The rectangular tongue 27 is, however, shaped to provide a curved bearing or guide 29 having the same

radius of curvature as the opening 30 in the lower flange 11. This provides a bearing for the ribbon spool shaft intermediate the flanges 10 and 11, and although the bearing does not completely surround the shaft, it is sufficient to answer the purpose of holding the spool and of guiding the spool onto the shaft.

I claim:

- 10 1. A ribbon spool for typewriters having an end flange of sheet metal, said flange having a portion partially severed therefrom and bent inwardly toward the axis of said spool to form a bearing member for said spool and to provide an opening through said flange outside of said bearing member.
- 15 2. A ribbon spool for typewriters comprising a pair of end flanges connected by a hollow core member, one of said flanges having a portion partially severed therefrom and bent inwardly to a position between said flanges and spaced inwardly from the wall of said core member, said inwardly bent portion being curved to form a bearing for a
- 20 25 ribbon spool shaft.
- 30 3. A ribbon spool for typewriters having an end flange of sheet metal, said flange having a portion severed therefrom along a part of the peripherery surrounding said severed portion, said portion being bent inwardly along the unsevered part of the periphery thereof and being curved about the axis of said spool as a center to form a bearing member for said spool for engaging a ribbon spool shaft.
- 35 4. A ribbon spool for typewriters comprising a pair of end flanges of sheet material, a core member of sheet material bent into cylindrical formation and secured to said end flanges, said core member having an opening at one side thereof, one of said flanges having a portion partially severed therefrom adjacent the opening in said core member, said partially severed portion being bent inwardly and curved about the axis of said spool as a center to form a bearing member for said spool arranged to engage a ribbon spool shaft.
- 40 45 5. A ribbon spool for typewriters having

an end flange of sheet metal, said flange having a substantially rectangular portion severed therefrom along three sides thereof, said portion being bent inwardly along the fourth side thereof, the edges of said inwardly bent portion being curved to form a bearing member for said spool arranged to engage a ribbon spool shaft.

6. A ribbon spool for typewriters comprising end flanges spaced from one another, and a guide positioned intermediate said flanges for directing said spool onto a ribbon spool shaft, said guide being tapered toward the center of the spool from the end thereof at which the shaft enters the spool.

7. A ribbon spool for typewriters comprising end flanges spaced from one another, and a guide member supported from one of said flanges and arranged intermediate said flanges for directing said spool onto a ribbon spool shaft, one end of said spool being provided with a bearing for the shaft, said guide being tapered toward the center of the spool from said end.

8. A ribbon spool for typewriters comprising a core member, and a guide arranged adjacent the axis of said core member and spaced inwardly from the ends thereof for directing said spool onto a ribbon spool shaft, one end of said spool being provided with a bearing for the shaft, said guide being tapered toward the center of the spool from said end.

9. A ribbon spool for typewriters comprising a pair of end flanges, a core member for spacing said flanges relative to one another, and a projection secured to one of said flanges and extending toward the other thereof but spaced from said other flange, said projection having a guide member thereon for engaging a ribbon spool shaft to guide said spool onto said shaft, the end of said spool having said projection thereon being also provided with a bearing for said shaft substantially in the plane of said end.

In testimony whereof I have signed my name to this specification on this 30th day of March A. D. 1920.

OTTO A. HOKANSON.
